UNITED STATES PATENT OFFICE.

REED JONES AND LOUIS TRAUNG, JR., OF SAN FRANCISCO, CALIFORNIA.

LABEL.

1,203,003.

Specification of Letters Patent.

Patented Oct. 31, 1916.

Application filed April 26, 1915. Serial No. 26,666.

To all whom it may concern:

Be it known that we, REED JONES and LOUIS TRAUNG, Jr., citizens of the United States, and residents of the city and county 5 of San Francisco and State of California, have jointly invented a new and useful Improvement in Labels, of which the following is a specification.

Our invention relates to labels for cartons 10 and the like wherein the said label is formed of one piece comprising side and end portions and tabs formed integral with said end portions, the label being arranged to entirely inclose and thereby hermetically seal 15 a carton; and the objects of our invention are, first, to provide a one piece label arranged to entirely inclose, and thereby hermetically seal, a carton or the like; second, to eliminate the labor and expense of applying 20 separate end labels to a carton or the like, and third, to provide a simple and improved label having end portions adapted to entirely inclose the ends of a carton and formed integral with the body portion of the 25 label and adapted to entirely inclose the sides of the carton and to overlap tabs formed integral with the end portions and pasted firmly to the sides of the carton. We accomplish these several features by means 30 of the device disclosed in the drawings forming a part of the present specifications wherein like characters of reference are used to designate similar parts throughout the said specification and drawings, and in 35 which—

Figure 1 is a plan view of the label disclosed in a slightly folded position, the dotted rectangles indicating the area of the printed or photolithographed portion of the 40 label on the other or under side thereof. Fig. 2 is a perspective view disclosing the first position in which the label is applied to a carton. Fig. 3 is a perspective view disclosing the second position. Fig. 4 is a 45 perspective view disclosing the third position.

Referring to the drawings the numeral 1 is used to designate a one piece label, substantially T-shaped, comprising the end portions 50 2 and 3 and what we term the side portions 4, 6, 7 and 8. The end portions 2 and 3, and the top side portion 4 are in alinement and form the top of the T while the remaining side portions 6, 7 and 8 are 55 also in alinement and form the stem of the

T, said side portions 6, 7 and 8 being arranged transversely to the side portion 4 and the end portions 2 and 3. Rectangular tabs 9, 11 and 12 are formed integral with the end portion 2 while similar tabs 14, 15 and 16 are formed integral with the end portion 3. A tab 17 is formed integral with the top side portion 4 of the label 1 and is in alinement with the tabs 12 and 16 of the end portions 2 and 3 respectively. The small square portions 18 and 19, formed at the junctions of the tabs 9 and 11, and 11 and 12 respectively, and the square portions 21 and 22 formed at the junction of the tabs 14 and 15, and 15 and 16, are folded diagonally so that when the said end portions 2 and 3 of the label 1, and the tabs 9, 11, 12, 14, 15 and 16 are pasted at right angles onto a carton 5 that the said square portions 18, 19, 21 and 22 will form flat triangular portions which may be folded back onto certain of the tabs and be firmly pasted in position so as to entirely inclose the ends of the carton 5.

The operation of pasting the label 1 onto a rectangular carton so as to entirely inclose and thereby hermetically seal the same is as follows: The label 1 is laid approximately flat as disclosed in Fig. 1 of the drawings, with the printed or lithographed side down. A rectangular carton 5 or the like is placed upon the side portion 4 of the label 1 and the end portions 2 and 3 are pasted firmly to the ends of the said carton 5. The tabs 9, 12, 14 and 15 of the end portions 2 and 3 respectively, are first pasted onto the sides near the ends of the carton 5 and the tabs 11 and 15 are then firmly pasted onto the top side of the carton near the ends thereof, which arrangement will cause the square portions 18, 19, 21 and 22 to fold diagonally as disclosed in Fig. 2 of the drawings. This will also cause a diagonal fold between the tabs 12 and 17, and the tabs 16 and 17 so that the said tab 17 may be easily pasted onto the top side of the carton 5 at right angles to the side portion 4 of the label 1, to which the said tab 17 is secured. Likewise, a diagonal fold will be formed between the tabs 9 and 14 and the side portion 6 of the label 1 as disclosed in Fig. 2 of the drawings. After the diagonals formed by the folded square portions 18, 19, 21 and 22 are pasted onto the tabs 9, 12, 14 and 16, the package or carton 110

5 is turned over onto the side portion 6 of the label 1 as disclosed in Fig. 3 of the drawings, and the said side 6 is firmly pasted onto the then under side of the carton and over and onto the tabs 9 and 14 and the diagonals formed by the square portions 18 and 21 pasted thereon. The carton 5 is now again turned over onto the side portion 7 of the label 1, the said side portion 7 being thereby firmly pasted over and onto the tabs 11 and 15. The carton 5 and the label 1 pasted thereon will now appear as disclosed in Fig. 4 of the drawings, with the last or remaining side portion 8 of the label 1 extended.

By again turning the carton over and onto the side portion 8 of the label 1 the same will be firmly pasted onto the said carton 5 and onto the tab 17, the diagonals formed by the square portions 19 and 22 and onto and over the tabs 12 and 16, thereby entirely inclosing and hermetically sealing the said carton 5.

It is obvious from the foregoing that we have provided an improved label arranged to entirely inclose and thereby hermetically seal a carton or the like. It is also evident that we have provided an improved one piece label arranged to eliminate the labor and expense of applying separate end labels thereby providing a more closely sealed package at less expense and labor in a shorter period of time.

The details of construction are so susceptible to variation that we do not wish to confine ourselves to the precise construction shown herein but rather to avail ourselves of any modification that may fall properly within the scope of our invention.

Having thus described our invention what we claim as new and desire to secure by Letters Patent is—

1. A one piece T-shaped label comprising side and end portions arranged to entirely inclose the sides and ends of, and thereby hermetically seal, a rectangular carton or the like; and tabs formed integral with the end portions and one side portion of the label, said tabs first engaging the sides of a carton adjacent the ends thereof and the side portions of the label being secured over

and onto the said tabs and onto the said side portions of a carton or the like.

2. A one-piece T-shaped label comprising side and end portions arranged to entirely inclose the sides and ends of, and thereby hermetically seal, a rectangular carton or the like; and tabs formed integral with one side portion and the end portions of the label, said tabs and end portions engaging the ends and the sides of a carton adjacent the ends thereof, and the said side portions of the label engaging and inclosing the sides of the carton and the tabs secured thereto.

3. A one piece T-shaped label comprising side and end portions arranged to entirely inclose the sides and ends of, and thereby hermetically seal, a rectangular carton or the like; and tabs formed integral with one side and the end portions of the label and engaging the ends and that portion of the sides of the carton adjacent the ends, and the side portions of the label entirely inclosing the sides of the carton and the tabs secured thereon.

4. A one piece T-shaped label comprising side and end portions arranged to entirely inclose the sides and ends of, and thereby hermetically seal, a rectangular carton or the like, one side portion and the end portions being in alinement and forming the top of the T and the remaining side portions of said label being also in alinement and forming the stem of the T; and tabs formed integral with the side and end portions in alinement, said end portions and tabs being secured to the ends and to a portion of the sides respectively, of the rectangular carton adjacent the ends thereof, and the remaining side portions of the label entirely inclosing the sides of the carton and the tabs secured thereto.

In witness whereof we hereunto set our signatures in the presence of two subscribing witnesses.

REED JONES.
LOUIS TRAUNG, JR.
